Des. 211,026
Patented May 14, 1968

211,026

MUSIC BOX AMPLIFIER OR SIMILAR ARTICLE

Ying-Tsai Juan, 460 1-chome, Nakayama-cho,
Ichikawa, Japan

Filed Apr. 14, 1967, Ser. No. 6,714

Term of patent 3½ years

Claims priority, application Japan Mar. 10, 1967

(Cl. D26—14)

FIG. 1.

FIG. 5.

FIG. 2.

FIG. 3.

FIG. 6.

FIG. 4.

FIGURE 1 is a front elevation of a music box amplifier or similar article, showing my new design;

FIG. 2 is a bottom view thereof;

FIG. 3 is a rear elevation thereof;

FIG. 4 is a top plan view thereof;

FIG. 5 is an end view thereof, seen from the right of FIG. 1; and

FIG. 6 is an end view thereof, seen from the left of FIG. 1.

I claim:

The ornamental design for a music box amplifier or similar article, as shown.
